DEVICE FOR THE PRODUCTION OF SMOKED MEAT AND SAUSAGES

Hans Poppenburg, Borgholzhausen, Germany

Application July 7, 1955, Serial No. 520,559

2 Claims. (Cl. 99—261)

This invention relates to a process and a device for the production of smoked meat and sausages.

Treatments of this type are generally performed in smoking chambers, smoking towers and boxes. The goods to be smoked are entered into the smoking chambers while being supported upon spears or other suitable carriers.

If chambers or hollow shafts for the smoking of the articles are used, the latter are upwardly and downwardly moved in these chambers by means of revolving chains. The required smoking heat is produced either directly beneath the suspended articles or in adjacent chambers. The required heat is passed into the lateral or the lower part of the smoking chambers by natural draft or by a blower.

All the hitherto known smoking chambers have the disadvantage of a non-uniform treatment of the goods; consequently, the presmoked articles remain longer in the smoking chambers than is desired; the quality and the appearance of the smoked goods suffers accordingly and insufficiently smoked parts of the goods are easily exposed to waste.

It is the object of the invention to eliminate these disadvantages.

With these objects in view a device for use in smoke treating of articles such as meat and sausages according to the present application comprises in combination a vertical elongated chamber structure, a door in the chamber structure adapted to be closed during the smoke treating operation and adapted to be opened, when desired, smoke supply means operable for delivering smoke to the lower portion of the chamber structure and forcing the smoke in an upward direction through the chamber structure, a circular grate rotatable in opposite directions about a vertical axis and disposed above the lower portion of the chamber structure, suspension means for the articles to be treated disposed on the grate and rotatable therewith about said axis, the suspension means including two stands, each positioned within one-half of the area of the grate. Also provided are supporting means for supporting the stands on the grate comprising a pair of rails for each stand so arranged on the grate and so disposed relative to the door said one stand may be moved on its pair of rails to and from its position on the grate through the door when the grate is in a predetermined position and, respectively, the other of the stands may be so moved when the grate has been rotated for one-half turn from said predetermined position. Single driving means are provided for continuously rotating the grate about its vertical axis in either one of the opposite directions through any desired number of revolutions and means for reversing the direction of the drive of the driving means so as to reverse continuous rotation of the grate in the vertical elongated chamber while the same is closed during the smoke treating operation. In this manner articles to be treated will be moved alternately in opposite directions transversely of the upward direction of movement of the smoke, when desired.

2

These smoking gases are circulated through the treating chamber whereby an essential saving of fuel and a shortening of the treating time results. The articles treated in conformity with the invention have a uniform color and a surprising preserving capacity which is important for their durability, as well as the durability of preserves made therefrom.

The invention will now be described more in detail and with reference to the accompanying drawing.

10 In the drawings,

Fig. 1 is a vertical sectional view of the instant device for smoking meat and articles made thereof;

Fig. 2 is a horizontal cross sectional view on line II—II of Fig. 1; and

Fig. 3 is a horizontal cross sectional view on line III—III of Fig. 1.

The cylindrical smoke furnace or chamber 1 has an inner heat insulating layer 2. The furnace is provided with a horizontal grate 3. The smoke is generated from wood, saw mill waste, saw dust and similar materials.

A smoke generator 4 is located underneath the grate 3.

A second grate 5 is located above the grate 3; this grate 5 is rotatable about a vertical center shaft 8. The grate 5 is driven by means of a pair of pinions 9, a shaft 10 and 25 a multiple change-speed gear 11 from a reversible electromotor 12. The change-speed gear 11 and the reversible motor 12, which are located outside of the furnace 1, enable the driving of the grate 5 in both opposite directions and with different speeds. Rollers 6 supporting the grate 5 are uniformly distributed at the inner surface of the chamber or furnace 1, these rollers being carried by a ring 7 that is fastened to the inner wall of the furnace.

The furnace chamber 1 is so situated that the rotatable grate 5 is located at the height of the floor 13 or any other platform. In the space above the rotatable grate 5 which may be entered through an airtight closable door 14 (Fig. 2) there are placed the supports or stands 15 for the articles to be smoked. Rollers 16 of the stands 15 travel on parallel rails 17, said rails forming U-shaped supports. An air outlet tube 19 and an air circulating conduit or tube 20 are connected with smoke outlet stack 18 each of said tubes being adapted to be alternatively closed by a flap 21.

45 The conduit 20 leads to the suction connection 22 of a blower 23, the latter being connected with a conduit 24 for fresh air. One of the conduits 20 and 24 may be closed by a flap 25 while the other one is kept open. A conduit 26 leads from the blower 23, and a heater 27 is built into the conduit 26. Conduit 26 leads into an annular tube 28, Fig. 3, which surrounds the smoke generator 4 and is provided with inwardly directed air exits 29. The smoking gases expelled through the exits 29 will move upwardly.

55 The above described arrangement makes it possible to suck through blower 23 the fresh air supplied by conduit 24 and the smoke produced by generator 4. This is achieved by closing the discharge conduit 19 and blowing air and smoke from below into the furnace, whereby a continuous circuit is obtainable. Any cooling of the device is reduced to a minimum by the insulation 2 of the furnace 1 and the insulation of tubes 20 and 26. The unavoidable heat loss by the heating of the treated articles and their supports is compensated for by the heater 27, 60 whereby the temperature in the interior of the furnace may be accurately controlled.

The device enables the generation of the required quantity of smoke by consumption of a surprisingly small amount of fuel such as wood or saw dust. Consequently 65 the production of steam released by the treated articles will be reduced which in many instances, is a great advantage.

The air circulation is controlled by the blower 23 which may be operated at different speeds. By a speeded-up supply of air and smoke the smoking process is greatly shortened and the processing of the treated articles intensified which is of great advantage with regard to the preservation of the treated articles and preserves made from the same.

In certain cases it is desirable to combine with the addition of smoke to the air an admixture of steam. This admixture of steam may be obtained by repeatedly conducting the steam released from the treated materials through the blower 23 while the supply of fresh air 24 and the air exit 19 is completely closed by the flaps 21 and 25. In this manner the pores for the reception of the preserving smoke vapours may be kept open for any desired time. If the treatment with steam is to be carried out at the conclusion of the smoking treatment a nozzle may be used for this purpose or steam may be entered from the outside.

The instant smoking furnace is successfully applicable to the hot smoking of canned sausages. For such a process, it is advisable to operate the last two thirds of the smoking procedure under maintenance of relatively little air moisture. This object is obtained by circulating during this period of smoking only the dry air produced in the heater 27.

The articles to be smoked are turned in the furnace during the entire smoking procedure and the direction of rotation of the grate 5 is preferably changed at certain time periods by a change of the polarity of the motor 12, whereby a uniform coloring and preservation is attained of the treated articles. The rotational speed of the grate 5 may be adjusted by the gear 11.

Upon termination of the smoking process the air discharge conduit 19 is opened by shifting of the closure flap 21, whereby the smoke contained in the apparatus may escape through conduit 19. Now the door 14 is opened and the smoked articles removed from the stand 15 without the working personnel being exposed to the smoke.

Hereupon the furnace is again charged, the door 14 closed and the smoking procedure started again.

The smoke generator 4 may be positioned outside of the furnace. In this case the smoke and the hot air are conducted into the lower part of the furnace by a common conduit.

Since certain changes in carrying out the above invention could be made without departing from the scope thereof, it is intended that all matter contained in the above description or shown in the accompanying drawings shall be interpreted as illustrative and not in a limiting sense.

It is accordingly desired that in construing the breadth of the appended claims they shall not be limited to the specific exemplifications of the invention described herein.

Having thus described the invention, what I claim as new and desire to be secured by Letters Patent, is as follows:

1. A device, for use in smoke treating of articles such as meat and sausages, comprising in combination, a vertical elongated chamber structure; a door in said chamber structure adapted to be closed during the smoke treating operation and adapted to be opened, when desired; smoke supply means operable for delivering smoke to the lower portion of said chamber structure and forcing the smoke in an upward direction through the chamber structure; a circular grate rotatable in opposite directions about a

vertical axis and disposed above said lower portion of said chamber structure; suspension means for the articles to be treated disposed on said grate and rotatable therewith about said axis, said suspension means including two stands, each positioned within one-half of the area of said grate; means for supporting said stands on said grate comprising a pair of rails for each stand so arranged on said grate and so disposed relative to said door so that one stand may be moved on its pair of rails to and from its position on the grate through said door when said grate is in a predetermined position and, respectively, the other of said stands may be so moved when said grate has been rotated for one-half turn from said predetermined position; single driving means for continuously rotating said grate about said vertical axis in either one of said opposite directions through any desired number of revolutions; and means for reversing the direction of the drive of said driving means so as to reverse continuous rotation of said grate in said vertical elongated chamber while the same is closed during the smoke treating operation, whereby said articles to be treated will be moved alternatively in opposite directions transversely of said upward direction of movement of said smoke, when desired.

2. A device, for use in smoke treating of articles such as meat and sausages, comprising in combination, a vertical elongated chamber structure; a door in said chamber structure adapted to be closed during the smoke treating operation and adapted to be opened, when desired; smoke supply means operable for delivering smoke to the lower portion of said chamber structure and forcing the smoke in an upward direction through the chamber structure; a circular grate having supporting means including an annular flange secured in said chamber, and a series of rollers between said grate and said flange, said flange forming a track for said rollers, said circular grate being rotatable in opposite directions about a vertical axis and disposed above said lower portion of said chamber structure; suspension means for the articles to be treated disposed on said grate and rotatable therewith about said axis; single driving means for continuously rotating said grate about said vertical axis in either one of said opposite directions through any desired number of revolutions; and means for reversing the direction of drive of said driving means so as to reverse continuous rotation of said grate in said vertical elongated chamber while the same is closed during the smoke treating operation, whereby said articles to be treated will be moved alternatively in opposite directions transversely of said upward direction of movement of said smoke, when desired.
